UNITED STATES PATENT OFFICE.

FREDERICK D. WEBER, OF NEW YORK, N. Y.

PAPER-FILE.

SPECIFICATION forming part of Letters Patent No. 642,027, dated January 23, 1900.

Application filed June 3, 1899. Serial No. 719,220. (No model.)

To all whom it may concern:

Be it known that I, FREDERICK D. WEBER, a citizen of the United States, residing in the city of New York, in the borough of Brooklyn and State of New York, have invented certain new and useful Improvements in Paper-Files, of which the following is a specification.

This invention relates to certain improvements in paper-files, and more especially such paper-files as are used by grocers, bakers, and other storekeepers generally for small memoranda, such as small accounts and other memoranda, which are filed alphabetically and used for making up the account when the rush of the day is over or at any convenient time; and the invention consists of a paper-file comprising a number of hinged leaves of stiff material and pockets formed of each side of each leaf, each pocket being formed of a stiff board, connected at its inner edge with the inner edge of the leaf and open at its top and outer side and connected with the lower end of the leaf by a folding gusset, as will be more fully described hereinafter and finally pointed out in the claim.

In the accompanying drawings, Figure 1 represents a perspective view of my improved paper-file; and Fig. 2 is a vertical transverse section on line 2 2, Fig. 1.

Similar letters of reference indicate corresponding parts.

Referring to the drawings, A represents a plurality of leaves, which are preferably made of press-board, cardboard, or other stiff material. The individual leaves are hinged together at the back by muslin hinges *a* and preferably placed in a suitable pasteboard cover B. The leaves are provided at their sides with tabs *t*, on which the letters of the alphabet or other desired classification are marked, said tabs being formed by cutting the leaf step-shaped, as shown in Fig. 1. Each leaf A is provided at each side with a pocket formed by an independent piece of pasteboard or other stiff material C, which is connected at its inner edge to the muslin hinge *a* of the leaf A and at its lower end by a folding gusset *a'* with the lower edge of the

leaf A. The upper end and outer side of the 50 pocket C are left open, so as to permit the insertion of the bills or memorandum-slips from the upper end or side into the pocket. This is readily accomplished, as the board C, which forms, with the leaf A, the pocket, gives conveniently to permit the insertion of the slips or bills, while when the file is closed the slips are firmly retained in the pockets by the pressure of the boards. When it is desired to insert a bill or slip, this is facilitated by lifting the upper outer corner of the board of the pocket C and inserting then the slips in the same, either sidewise or from the upper end. The collected slips can either be removed together or any one of the same removed by simply reading the headings and pulling out with the fingers the desired slip.

The file is designed to be used by storekeepers, tradespeople, &c., for filing bills, memoranda, and accounts of sales which are 70 received during the day, so that they are available at the close of the day or other convenient time for entering into the account-books. My improved paper-file may be used for filing the duplicate slips of the sales, 75 while the originals are handed over to the customer with the goods, the former serving to make up the accounts and render the bills to the customers.

Having thus described my invention, I 80 claim as new and desire to secure by Letters Patent—

The paper-file herein described, consisting of a number of hinged leaves of stiff material and pockets formed at each side of each leaf, 85 each pocket being formed of a stiff board connected at its inner edge with the inner edge of the leaf and open at its top and outer side and connected with the lower end of the leaf by a folding gusset, substantially as set forth. 90

In testimony that I claim the foregoing as my invention I have signed my name in presence of two subscribing witnesses.

F. D. WEBER.
